(57) **CLAIM**

The ornamental design for a digital canister gauge, as shown and described.

DESCRIPTION

FIG. 1 is a top perspective view of an embodiment of a digital canister gauge showing our new design;

FIG. 2 is a bottom perspective of the digital canister gauge illustrated in FIG. 1;

FIG. 3 is a left side view of the digital canister gauge illustrated in FIG. 1;

FIG. 4 is a front view of the digital canister gauge illustrated in FIG. 1;

FIG. 5 is a right side view of the digital canister gauge illustrated in FIG. 1;

FIG. 6 is a rear view of the digital canister gauge illustrated in FIG. 1;

FIG. 7 is a top view of the digital canister gauge illustrated in FIG. 1; and,

FIG. 8 is a bottom view of the digital canister gauge illustrated in FIG. 1.

The broken lines in the drawings illustrate the portions of the digital canister gauge that form no part of the claimed design.
